COASTER PAD

Maurice E. Nye, Barberton, Ohio; Willard L. Nye, executor of said Maurice E. Nye, deceased

Application June 22, 1951, Serial No. 15,639

Term of patent 14 years

(Cl. D44—24)

To all whom it may concern:

Be it known that I, Maurice E. Nye, a citizen of the United States, resident of the city of Barberton, county of Summit, and State of Ohio, have invented a new, original, and ornamental Design for a Coaster Pad, of which the following is a specification, reference being had to the accompanying drawings, forming a part thereof.

The essential features of my design reside in the portion shown in full lines.

I claim:

The ornamental design for a coaster pad, substantially as shown and described.

MAURICE E. NYE.
